UNITED STATES PATENT OFFICE.

GEORGE THOMAS COOKE, OF NEW YORK, N. Y., ASSIGNOR TO UNION METAL PRODUCTS COMPANY, OF CHICAGO, ILLINOIS, A CORPORATION OF DELAWARE.

END PLATE FOR RAILWAY BOX CARS.

Application filed January 11, 1924. Serial No. 685,594.

The end plates of railway box cars and their attachments to the framework of the car as formerly used have proven inefficient and defective. The horizontal force transmitted to the end plate by the end framing post broke them at their longitudinal center. On account of the weakness of the connection between the end plates and the side plates, the weaving and racking of the cars in service broke or loosened these connections, thereby allowing the roof framing to become distorted, resulting in leaky roofs and damaged lading.

This same weaving and racking of the cars in service distorted the side frames or trusses of the cars, resulting in inoperative side doors and ill-fitting side doors permitting rain and sparks to enter the car.

This same weaving and racking of the cars in service distorted the end framing of the cars contributing to the cause of leaky roofs and causing inoperative and ill-fitting end doors.

One of the objects of my invention is to provide a metallic end plate which can be used in the place of the usual wooden end plate having sufficient strength to perform its function as a frame member and also to resist the weaving and racking strains referred to heretofore.

Another object of the invention is to provide such a metallic end plate with connections to the side plates to resist the weaving and racking strains referred to heretofore and which connections assist in retaining the rectangularity of the roof framing, the side framing and the end framing.

Another object of the invention is to provide integral means in a metallic end plate to stiffen it to resist buckling and to transmit the stresses from the end posts as well as the corner posts to the side wall of the car.

Another object of the invention is to provide means or method of attaching such metallic end plate to the side plates of the car, whereby a bracing effect is obtained between such frame members to retain the desired angularity between them. This desired result is obtained by attaching the end plate to both the inner and outer sides of the side plate. The end plate is then a restrained beam which is considerably stronger than a loose end beam.

My improved end plate may be used to strengthen and reinforce a wooden end

plate already in a car or it may be used as an end plate by itself.

The metallic end plate may be used with a car having an all metal reinforced end or it may be used with a car having a wooden end retaining wall and metallic frame members.

Another object of the invention is to provide means of connecting a metallic end plate to both the inside and outside of the side wall of a railway box car.

In the drawings:

Fig. 1 shows the upper portion of an end elevation of a railway box car with my device applied thereon. 70

Fig. 2 is a plan view of Fig. 1.

Fig. 3 is a fragmentary side elevation of Fig. 1.

Fig. 4 is a section along line 4—4 of Fig. 1. 75

Fig. 5 shows the upper portion of an elevation of another type of railway box car.

Fig. 6 is a plan view of Fig. 5.

Fig. 7 is a fragmentary side elevation of Fig. 5. 80

Fig. 8 is a section along line 8—8 of Fig. 5.

Fig. 9 shows the device applied as a reinforcement to a wooden end plate already in the car. 85

The metallic end plate has a vertical portion 1 which has an integral vertical flange 2 secured to the corner post 3 by rivets 4 which rivets also secure it to the side plate 5. The upper portion 5 is bent to form a flange 6 conforming to the slopes of the roof, which flange is bent downwardly to form flange 7 which is secured to side plate 5 and corner post 3 by rivets 8 and also secured to side plate 5 by rivets 9. In this manner the metallic end plate is secured to both inside and outside of the side plate 5. The upper flange 6 forms a gusset connection between the side plate 5 and portion 1 of the end plate, thereby preserving the rectangularity 90 of the roof frame. The portion 1 of the metallic end plate has considerable vertical depth at the center of the car and is reinforced against buckling by corrugation 10 so that it has sufficient strength as a frame member. The portion 1 also has considerable vertical depth adjacent the corner post 3 so that it forms a gusset and preserves the rectangularity of the end frame of the car. The portion 1 is secured to the corner post by riv- 105

110

ets 11. The flange 2 extends back on the side of the car a sufficient distance to give it strength as a gusset to preserve the rectangularity of the side frame of the car. This arrangement gives a very strong construction at the junction of the side, top and end planes of the car, which is a very vital spot, and in former designs, has been a very weak spot.

The corrugation 10 not only prevents the vertical portion 1 of the metallic plate from buckling, as mentioned heretofore, but is in itself a beam which transmits the loads imposed upon it to the side frame of the car. In the drawings these loads are carried to the side plate which is part of the side frame. The bottom part of the corrugation 10 is horizontal and substantially parallel to the lower edge of portion 1, while the upper part of the corrugation 10 is preferably parallel to the flanges 6. This arrangement gives a wider corrugation adjacent its longitudinal center which is, therefore, stronger at such point. The lower part of portion 1 overlies the end post 17 and corner post 41 (see Figs. 9 and 5) so as to retain them in proper position and prevent them from "kicking out" at the top. As shown in Fig. 9, the corrugation 10 preferably overlies the upper ends of the corner post and end post. The corrugation terminates adjacent the side plates. Any thrust, therefore, due to shifting lading, etc., is transmitted to the corrugation and by said corrugation to the side plates.

The end frame post 12 performs two functions: First, it resists the impact of the lading through the lining boards 13 which impact is transmitted to the metallic end plate by rivets 14 and 15. It will be noted that the end post 12 spans the corrugation and that rivets 14 and 15 are on opposite sides of the corrugation 10 which not only effectually carries the stress to the corrugation, but prevents the corrugation from failing by opening up. Secondly, the end post is a part of the end frame and assists in resisting the stresses tending to distort the frame. On account of the great depth of portion 1 the rivets 14 and 15 are spaced apart, giving a stronger connection than if they were placed close together. Connection angle 16 may be used to strengthen the connection between the end post 12 and the portion 1.

Figs. 5 to 8 inclusive show the device as designed for application to a car having a metallic end wall 30 and a wooden side plate 31. Such a car is not usually provided with any end post, but otherwise the mechanical advantages claimed for the construction described herein are substantially the same.

The metallic end plate is provided with the vertical portion 32 which has the integral flange 33 extending along and secured to the side frame of the car by bolts 34, 35 and 36.

The portion 32 is provided with corrugation 37. The bottom edge of portion 32 is offset 65 at 38 to overlap the upper edge of metallic wall 30. As this metallic wall 30 is flanged to extend around the side wall of the car the bottom edge of the offset portion 38 is also extended around the side of the car. The 70 upper edge of the metallic end plate is provided with an integral flange 39 which is flanged downwardly to form flange 40 which is secured to side plate and flange 33 by bolts 34.

Fig. 9 shows a metallic end plate used to reinforce a wooden end plate which is already in the car. It is an expensive operation to remove and replace one of these old wooden end plates; it is more economical to 80 reinforce it by using a metallic end plate as described herein.

The corrugation may be formed to extend inwardly, as shown in Fig. 4, or outwardly, as shown in Figs. 8 and 9, without deviating 85 from the scope of this invention.

In the drawings the roof of the car has been eliminated for simplicity.

I claim:

1. In a railway box car having side plates, corner posts and end posts; a metallic end plate secured to said side plates and overlying said corner posts, said end plate provided with an integral corrugation, the end post secured to said end plate on both sides of the 95 corrugation.

2. In combination with the side plates of a railway box car, a metallic end plate having a vertical portion and a portion conforming to the slopes of the roof, both portions secured to said side plates at their opposite ends, said vertical portion having an integral corrugation formed therein with its upper parts parallel to the slopes of the roof and with its lower part horizontal. 100

3. In a railway car, the combination of side plates, a metallic end plate having an integral corrugation formed therein extending substantially to the opposite side plates, said end plate provided with an integral 110 flange conforming substantially to the slopes of the roof, and end posts terminating adjacent said flange and secured to said end plate on both sides of said corrugation.

4. In a railway car, the combination of side plates, a metallic end plate having an integral corrugation formed therein extending substantially to the opposite side plates, said end plate provided with an integral 115 flange conforming substantially to the slopes of the roof, end posts terminating adjacent said flange and secured to said end plate on both sides of said corrugation, and corner posts terminating adjacent said flange. 120

GEORGE THOMAS COOKE.
